UNITED STATES PATENT OFFICE.

FREDERICK ARTHUR STEVENS, OF PROVIDENCE, RHODE ISLAND, ASSIGNOR TO
STEVENS AND COMPANY, INCORPORATED, OF PROVIDENCE, RHODE ISLAND,
A CORPORATION OF RHODE ISLAND.

DESIGN FOR A LENS-CLIP OR SIMILAR ARTICLE.

56,484.

Specification for Design.

Patented Oct. 26, 1920.

Application filed November 26, 1919. Serial No. 340,949. Term of patent 14 years.

To all whom it may concern:

Be it known that I, FREDERICK ARTHUR STEVENS, a citizen of the United States, residing at Providence, in the county of Providence and State of Rhode Island, have invented a new, original, and ornamental Design for a Lens-Clip or Similar Article, of which the following is a specification, reference being had to the accompanying drawing.

The single figure of the drawing is an elevation of the lens clip or similar article embodying my new design, shown in position upon a lens.

The design comprises a lens strap or end piece 1 having an ear 2 of the configuration shown. The strap or end piece 1, with the ear attached, may be mounted at either end of a nose bridge 3 or 4 or at the end of a temple 5. In order that the essential

feature of the invention may be made to stand out in the drawings, the ear 2 is shown in full lines and the body portions of the nose bridge and the temple in dotted lines.

The material or leading feature of the design consists of the terminal configuration of the ear, comprising a line 6 substantially at right angles to the general direction of extension of the clip and short lines 7 that meet the line 6 and merge into the adjacent rounded contour 8.

I claim;

The ornamental design for a lens clip or similar article substantially as shown and described.

Signed at Providence, in the county of Providence and State of Rhode Island, this 24th day of November, 1919.

FREDERICK A. STEVENS.
